UNITED STATES PATENT OFFICE.

WILLIAM DOWLING, OF ST. LOUIS, MISSOURI, ASSIGNOR TO MESKER BROTHERS IRON COMPANY, OF ST. LOUIS, MISSOURI, A CORPORATION OF MISSOURI

METALLIC NEWEL CONSTRUCTION.

1,127,743.

Specification of Letters Patent.

Patented Feb. 9, 1915.

Application filed May 20, 1914. Serial No. 839,749.

To all whom it may concern:

Be it known that I, WILLIAM DOWLING, a citizen of the United States, residing at the city of St. Louis, State of Missouri, 5 have invented a certain new and useful Improvement in Metallic Newel Construction, of which the following is a full, clear, and exact description, such as will enable others skilled in the art to which it appertains to 10 make and use the same, reference being had to the accompanying drawings, forming part of this specification.

My invention relates broadly to metallic building structures, and specifically to a 15 form of newel post for metallic stairway construction.

For reasons of economy, it is desirable in the construction of metallic stairways to have as many of the parts of more or less 20 standard construction so that they may be kept constantly in stock and utilized to fill orders calling for a variety of disposals or dimensions. This enables the filling of orders rapidly and at a considerable saving 25 over instances wherein it is necessary to roll and form as well as fabricate the material.

It is the purpose of my invention to provide a form of newel post of standard size 30 which may be adapted to use in connection with various sizes of associated building structure members without requiring shaping or fabrication.

As will be understood from the accompanying drawings, in which—

Figure 1 represents the application of my invention, Fig. 2, a side elevational detail, and Fig. 3 a cross section substantially on line 3—3 of Fig. 2. 40 The invention contemplates a column member 1 formed of sheet metal, and suitably finished at its upper end with a cap 2. An adjustable portion 4 has a reduced portion 5 adapted to extend slidably within the 45 column member 1. Said reduced portion extends only part-way of the depth of the column member 1 and the adjustable member 4, leaving a shoulder 6 on the latter. By sliding the adjustable member 4 in-

wardly or outwardly relative to the column 50 member 1, the distance between the shoulder 6 and the bottom of the column member 1 may be adjusted. The adjustable member is suitably finished at its lower end by a cap 7. This relative adjustability of members 55 1 and 4 enables the use of the newel in connection with various depths of structural members 8 upon which the newel and the stair structure are supported. In view of the fact that the structural members 60 vary considerably in depth, the adjustability of the newel obviates a great deal of fabricating when the newels are installed. In the use of my improved form, it is necessary simply to adjust the member 4 relative 65 to the member 1, so that there is the proper spacing between the shoulder 6 and the bottom of the member 1 to accommodate the structural member 8. The members 1 and 4 are then secured in the proper relative position by suitable fastenings 9.

I have illustrated the column member 1 and the adjustable member 4 as quadrilateral in contour, although, of course, it is 75 obvious that they may be of other form.

I am aware also that other changes may be made in the structure without departing from the spirit of the invention.

What I claim is:

1. A newel comprising a column member, 80 an adjustable member mounted thereon, a shoulder on said adjustable member, which shoulder is adapted to coöperate with the column member to embrace a structural member, and means for securing the adjustable member to said column member.

2. A newel comprising a pair of members having overlapping portions, one of which members is provided with a cut-away portion adapted to receive a structural member, 90 and a shoulder portion adapted to coöperate with a portion of the other member for the purpose described.

3. A newel formed in two parts, one of which telescopes the other and one of said parts being cut away to form a shoulder adapted to coöperate with a portion of the other part to engage a structural member.

4. A newel formed in two parts, one of which telescopes the other and one of said parts being cut away to form a shoulder adapted to coöperate with a portion of the other part to engage a structural member, and means for rigidly connecting said parts.
5. In testimony whereof I hereunto affix my

signature in the presence of two ~~witnesses~~, this twelfth day of May, 1914.

WILLIAM DOWLING.
